UNITED STATES PATENT OFFICE.

FRANK J. LARSON, OF SPRINGBROOK, WISCONSIN.

PAINT-DISPENSING CAN.

1,323,875.

Specification of Letters Patent.

Patented Dec. 2, 1919.

Application filed August 31, 1917. Serial No. 189,140.

To all whom it may concern:

Be it known that I, FRANK J. LARSON, a citizen of the United States, and resident of Springbrook, in the county of Washburn 5 and State of Wisconsin, have invented certain new and useful Improvements in Paint-Dispensing Cans, of which the following is a specification.

This invention relates to improvements in dispensing cans and it is the dominant object of the invention to provide a paint dispensing can having a fountain brush connected thereto and adapted to receive its supply of paint from the can, thereby eliminating the continual dipping of the brush 10 into paint and preventing considerable waste.

Another and equally important object of the invention is to provide the can with a fluid forcing piston, which piston has a screened opening formed therein for straining the paint or other coating fluid poured thereinto, thus preventing the clogging of the can.

Among other aims and objects of the invention may be recited, the provision of a can of the character mentioned with a view to compactness, and in which the number of parts are few, the construction simple, 25 the cost of production small, and efficiency and operation high.

The invention consists, furthermore, in the novel arrangements and combinations of the parts of the device, as well as in the details of the construction of the same, all of which will be more fully described in the following specification, and then finally embodied in the clauses of the claim, which are appended to the specification and which 35 form an essential part of the same.

The invention is clearly illustrated in the accompanying drawings, in which—

Figure 1 is a vertical section through the improved can; and

Fig. 2 is a horizontal section therethrough.

Similar characters of reference refer to similar parts throughout the several views of the drawings.

Having more particular reference to the drawings, 1 represents the paint dispensing can having an opening formed adjacent the bottom thereof, which opening is engaged by one end of a flexible conduit 2, the said conduit extending upwardly adjacent the 55 side of the can and being secured thereto

by a bracket 3. A cover 4 is provided for the can and carries a handle 5 thereon, whereby the placing or removing of the same therefrom will be facilitated.

Movably arranged in the can 1 is a piston 6. 60 An opening is formed preferably concentrically of the piston 6 and has a screen 7 arranged thereover, whereby said coating fluid as poured into the can will be strained, thus eliminating the presence of clods of 65 paint and allowing the can to properly function at all times. A screw threaded nut 8 is arranged adjacent the opening in the piston and is adapted to have turned into engagement therewith a complementally 70 screw threaded closure cap 9. To enable the user to move the piston 6 upwardly to an inoperative position, a handle 10 is pivotally engaged with the same, while hooks 11 are loosely engaged with the opposite portions 75 thereof and are adapted to be engaged with other hooks 12 immovably arranged upon the inner sides of the can 1.

Engaged with the under side of the piston 6 through the medium of brackets 13 is a 80 contractile coiled spring 14, the lower convolution of which is engaged by set screws 15 which are passed through the lower portion of the can into engagement therewith. By so connecting the piston 6, it will be 85 readily understood that a downward pull is normally exerted thereon, and such fluid as is arranged beneath the same will be forced through the outlet opening and the conduit 2. 90

A brush 16 having a hollow handle and a plurality of longitudinal channels formed in the head thereof communicating with said hollow handle and opening into the bristles of the brush is provided. The handle of 95 the brush 16 at its end 17 is suitably connected with the end 18 of the conduit 2. To permit the passage of paint through the brush to be controlled at will by the operator, a valve 19 is arranged therein.

Upon one side of the can 1, a hook 20 is arranged and serves as means for supporting the can upon a rung of a ladder or other suitable supports.

In operation, when filling the can, the 105 cover 4 is removed and the piston 6 pulled upwardly whereupon the hasps 11 are engaged with hooks 12 arranged therein. With the piston in that position, the closure cap 9 is removed and paint poured through 110

the opening formed in the piston, the screen 7 thoroughly straining the same and preventing the passage of clod into the can. When filled, the closure 4 is replaced subsequent to the disengaging of the hasps or hooks 11 with the hooks 12. The spring 14 will normally exert a downward pull on the piston 6, and as hereinbefore stated, cause the forcing of the paint from the can 10 through the conduit 2 onto the bristles of the brush. By reason of the flexible connection to the can, the brush can be readily worked back and forth over an object being coated.

15 Manifestly, the construction shown is capable of considerable modification and such modification as is within the scope of my claims, I consider within the spirit of my invention.

20 I claim:—

1. In a device of the character described, a receptacle having an outlet opening

formed adjacent its bottom, a piston provided with an opening movably arranged in the receptacle, a strainer positioned over said opening, means for closing the opening at times, and spring means engaged with the piston and the bottom of said can for normally moving the same downwardly.

2. In a device of the character described, 30 a receptacle having an outlet opening formed adjacent its bottom, a piston having an opening movably arranged in the receptacle, a strainer arranged over said opening, a cap for closing the opening at times, means for 35 normally moving said piston downwardly in the receptacle, and other means arranged adjacent the upper end of the receptacle and engageable with the piston for maintaining the same in raised position.

40 In testimony whereof, I affix my signature hereto.

FRANK J. LARSON.
